11 Claims. (Cl. 167—87)

The present invention relates to a cosmetic composition suitable for daily use in the care of the hair. More particularly it relates to hair cleansing and grooming compositions such as hair lotions, tonics, shampoos and the like which may be used in the daily toilet.

In accordance with the present invention a cosmetic composition suitable for daily use in the care of the hair and scalp comprises a substantially non-volatile organic toilet agent for the daily care of the hair and a diamide compound having the formula

wherein X is selected from the group consisting of oxygen and sulfur, R₁, R₂, R₄ and R₅ are selected from the group consisting of hydrogen, alkyl, alkyloxy and acyl, and R₃ is selected from the group consisting of hydrogen and alkyl, said R₁, R₂, R₃, R₄, and R₅ containing up to two carbon atoms each, and from 40 to 99.45% of a volatile aqueous solvent medium, said composition having a pH of from 4 to 10 and being free of reducing agents. Suitable such compounds include biuret, thiobiuret, dithiobiuret, and their water- and alcohol-soluble mono- and polyalkyl, -alkyloxy and -acyl derivatives wherein the alkyl, alkyloxy and acyl groups have in general not more than 2 carbon atoms, e.g. 1-methyl-biuret, 3-methyl-biuret, 1-ethyl-biuret, 1,5-dimethyl-biuret, 1,3,5-trimethyl-biuret, 1-hydroxymethyl-biuret, 1,5-dihydroxymethyl-biuret, 1-acetyl-biuret, 1-formyl-5-acetyl-biuret, 1,5-dimethyl-1-acetyl-biuret, 1,3,5-trimethyl-1-acetyl-biuret, 3-ethyl-1-acetyl-biuret, 1-methyl-thiobiuret, 1-ethyl-thiobiuret, 1-acetyl-thiobiuret, 1-hydroxymethyl-thiobiuret, and 1-methyl-dithiobiuret.

The cosmetic compositions of the present invention may be prepared in a wide variety of physical forms. They may be liquids, pastes or solids and may consist of one or more phases. They may, for example, constitute a single aqueous or aqueous-alcoholic phase, or may comprise an aqueous and a separate oily phase as in two layer systems or emulsions of the water-in-oil or oil-in-water types.

The instant compositions and their constituents are skin-compatible, being suitable for periodic use at short, i.e. daily or at the most weekly, intervals, as distinguished from decorative or treating compositions such as hair dyeing or waving compositions which can be used only at much greater intervals. Thus it is contemplated that the present cosmetic compositions may be prepared in the form of daily hair grooming products such as hair lotions, hair dressings, hair tonics and the like, or they may be prepared in the form of hair cleansing products such as shampoos, the non-volatile organic toilet agent for daily care of the hair being present in each instance in an amount from 0.5 to 98% by weight of the composition.

In the case of hair grooming compositions, the non-volatile organic toilet agent for the daily care of the hair

is an agent which facilitates grooming of the hair and helps to keep the hair in place. Such hair grooming agents include, e.g., castor oil, mineral oil, lower alkoxy-polyoxy lower alkylene glycols such as butoxypolyoxypropylene glycol, higher molecular weight copolymers of random mixtures of ethylene oxide and propylene oxide, esters of fatty acids such as isopropylmyristate or the coconut oil fatty acid ester of polyethylene glycol having an average molecular weight of about 400, polyhydric alcohols such as glycerol and propylene glycol, gums such as gum tragacanth, lacquers such as shellac, and the like. It is preferred to employ those substantially non-volatile organic hair grooming agents which have a molecular weight greater than about 75 and preferably greater than about 200 and which contain an alcoholic hydroxyl group such as the aforementioned glycols, polyhydric alcohols, polymerized alkylene oxides, and castor oil. The foregoing organic hair grooming materials desirably are employed in the instant hair grooming preparations in an amount from 0.5 to 50% and higher depending on the nature of the respective compound and its compatibility in the desired system.

In the case of hair cleansing compositions or shampoos, the non-volatile organic toilet agent for the daily care of the hair is a cleansing agent such as a water-soluble organic detergent. Preferably this detergent is an anionic sulfate or sulfonate, i.e. a sulfated or sulfonated compound having a hydrophobic substituent containing 8 to 26 carbon atoms, desirably from 12 to 18 carbon atoms, per molecule.

Detergents of this preferred type which may be suitably employed include the sulfuric acid esters of polyhydric alcohols incompletely esterified with higher fatty acids, e.g., coconut oil monoglyceride monosulfate and tallow diglyceride monosulfate; the long chain pure or mixed alkyl sulfates such as lauryl sulfate, cetyl sulfate, and higher fatty alcohol sulfates derived from coconut oil; the hydroxy sulfonated higher fatty acid esters such as, e.g., higher fatty acid esters of 2,3-dihydroxypropane sulfonic acid; the higher fatty acid esters of low molecular weight alkyloxy sulfonic acids, e.g., oleic acid ester of isethionic acid; the sulfated higher fatty acid alkyloxyamides such as, e.g., ethanolamide sulfates; the higher fatty acid amides of amino alkyl sulfonic acids, e.g., the lauric amide of taurine, and the like.

Other anionic synthetic detergents which may be employed in shampoos are the sulfonic acid salts of alkylated aromatic hydrocarbon compounds having an alkyl substituent containing 8 to 26 carbon atoms. The aromatic portion of the molecule may be mono- or polynuclear, e.g., benzene, toluene, xylene, naphthalene, phenanthrene, anthracene, etc., and may contain other substituents such as hydroxyl groups or short chain alkyl groups such as, e.g., in phenol, cresol, phenol ethers, toluene, xylene, etc. The long chain alkyl substituent of the alkylated aromatic molecule preferably is saturated and may be straight chain or branched. Representative long chain alkyl groups include the dodecyl, hexyl, octyl, nonyl, and decyl groups as well as mixed alkyls derived from fatty materials, cracked paraffins or polymers of lower mono olefins, etc. In general, the alkylated aromatic detergents employed will be a mixture of compounds having alkyl substituents of varying chain length since the chain length is dependent upon the sharpness of the fractionation of the aliphatic hydrocarbon used for the alkylation. The average chain length of the alkyl substituents should be in general from 9 to 15 carbon atoms and preferably between 12 and 14 carbon atoms.

These various anionic detergents are employed in shampoos prepared in accordance with the present invention in the form of their water-soluble salts. Thus, detergents may be used in the form of their alkali salts, e.g.,

as sodium, potassium or lithium salts, or as ammonium salts, as well as in the form of salts of nitrogen containing bases, e.g., as salts of low molecular alkyloamines such as mono-, di- and triethanolamine, and as mixtures of various of these salts.

Other anionic detergents which may also be employed include water-soluble alkyl phosphates, sulfated ethylene oxide condensates of hydrophobic materials such as higher fatty acids, fatty alcohols, alkyl aromatic hydrocarbons and the like, sulfonated oils, soaps such as sodium, potassium and triethanolamine soaps of higher fatty acids containing from 12 to 18 carbon atoms as well as mixtures of soaps being especially useful such as sodium laurate, sodium palmitate, sodium oleate and the potassium and/or triethanolamine soaps of coconut oil, palm oil, and tallow fatty acids.

Further suitable organic detergents include non-ionic detergents such as the lower alkylene oxide condensation products of hydrophobic compounds, e.g., the ethylene oxide condensation products with higher fatty acids, higher fatty alcohols or alkylated aromatic hydrocarbons, polypropylene glycols having a molecular weight greater than 900, amide and amine condensates such as fatty acid alkyl amides, e.g., N-bis(2-hydroxyethyl)-lauramide, and finally the condensation products of fatty acid chlorides with hydrolyzed natural proteins often referred to as lysalbinic acid derivatives.

Cationic detergents wherein a quaternary nitrogen atom is part of an open chain or heterocyclic structure, e.g., lauroyl pyridinium bromide, cetyl trimethyl ammonium chloride or cetyl pyridinium chloride may also be used alone or in combination with other compatible detergents. Suitable salts of cationic detergents are the chloride, bromide, acetate and sulfate.

Suitable detergents are furthermore the amphoteric detergents such as salts of the N-alkyl compounds of beta-amino propionic acid wherein the alkyl group is derived from a fatty acid such as the mixture of coconut oil fatty acids.

Shampoos in accordance with the present invention may be prepared in any convenient physical form and may consist of one or more phases. Thus such a shampoo may be a solid product such as a bar or a powder, or a clear, homogeneous single phase liquid such as an aqueous or aqueous-alcoholic composition, or it may contain two or more liquid or mixed liquid and solid phases, as in the case of cream-shampoos, lotion-shampoos, paste-shampoos, and the like. The foregoing detergents desirably comprise at least 5% and preferably from 15 to 40% of the instant shampoos when they are prepared in a liquid or paste form, and from 15 to 98% when the shampoo is prepared in the form of a solid composition.

The diamide compounds of the present invention constitute a minor proportion, on the order of 0.05 to 10% of the instant hair preparations, the most suitable amount depending on the characteristics desired. Thus, in a clear, homogeneous, single phase, aqueous type of hair preparation preferably an amount on the order of 0.25 to 1.0% of the composition is employed. In a single phase composition containing aqueous alcohol the present diamide compounds are more soluble and therefore preferably 0.25 to 2.0% may be employed. In solid or cream type hair preparations wherein the partly limited solubility of the diamide compounds is not a concentration-limiting factor, amounts of diamide on the order of up to about 10% may be used.

For example, an aqueous cosmetic composition may comprise from 0.05 to 10% of diamide, from 0.5 to 50% of the non-volatile organic toilet agent, and as the balance, e.g. 40-99.45%, a volatile aqueous solvent medium such as water or mixtures of water and a lower monohydric alcohol such as ethanol or isopropyl alcohol. In the preparation of a clear, homogeneous single phase aqueous shampoo, preferably 0.5 to 2% of one of the instant di-

amide compounds, 5 to 20% water soluble detergent, and 78-94.5% water and other components are used, whereas in a shampoo containing aqueous alcohol wherein said diamide compounds and detergents are each more soluble, 5 more than 2% of the diamide may be used in combination with 5 to 40% of the detergent, the balance being aqueous alcohol and other components. In solid, powder or cream shampoos amounts of 0.05 up to 10% of diamide are possible in combination with 15 to 98% of the detergent and a balance of water and/or other components.

The instant hair preparations may also contain as adjuvant materials various substances such as vitamins, hormones, cholesterol, lanolin, bactericides, plant extracts, buffers, and the like in compatible proportions, although the preparations should be free of substantial quantities of water insoluble solid substances which may be deposited on and clog the pores of the scalp. Desirably the present compositions have a pH of 4 to 10 as they appear to be most effective in this range.

The hair preparations of the invention exhibit unusually excellent hair grooming properties. They render the hair soft and manageable, impart a high gloss and luster, and are particularly effective in controlling or preventing the formation of dry flaky scales of sloughed-off skin.

The efficiency of aqueous compositions prepared in accordance with the present invention is favorably influenced by the presence of a water soluble material which reduces the surface- and/or interfacial-tension of water (e.g. alcohol in alcoholic hair tonics, soaps or synthetic detergents in shampoos, emulsifiers in hair dressings). The presence of these surface active materials is believed to reduce the interfacial tension between the aqueous phase containing the instant water soluble diamides and the hair and scalp so that soil and oily secretions are more easily displaced and eliminated, thus aiding in the grooming and care of the hair.

For the preparation of aqueous, alcoholic, or aqueous alcoholic hair tonics, liquid shampoos, hair creams of hair rinses, the diamides together with other desired water- or alcohol-soluble components may be dissolved at room temperature or elevated temperature in the amount of water, alcohol or aqueous alcohol required for the respective hair preparation. Thereafter, the toilet agent for the daily care of the hair may be added in the usual way, i.e. in the case of hair tonics, liquid shampoos or hair rinses the hair grooming agent may be added to the liquid containing the diamide of the invention, and in the case of hair creams of the oil-in-water or water-in-oil type, the liquid containing the diamide may be heated to 50-70° C. and emulsified with the molten fats, mineral oils or like hair grooming agents, the emulsion, if necessary, being homogenized thereafter.

Cream shampoos formulated in accordance with the present invention may be prepared by mixing an aqueous detergent paste with an appropriate diamide compound and any other desired components with stirring at an elevated temperature (40-60° C.).

Powder shampoos may be made by homogeneously mixing the desired components in a mixer.

Specific hair preparations according to the invention are illustrated by the following examples. All parts indicated are by weight unless otherwise specified.

EXAMPLE 1

Hair Lotion

To 56 parts of ethyl alcohol 96% and 6 parts of glycerine 98% in a suitable mixer 2 parts of biuret are added with stirring. After complete dissolution of the biuret, 0.19 part of perfume and 0.01 part of dyestuff are introduced as coloring for the lotion, and after short stirring 35.8 parts of deionized water are added. For clarification 0.1 part of magnesium carbonate is stirred into the solution and filtered off again.

EXAMPLE 2

Hair Lotion

	Parts
Ethyl alcohol 96%	60.0
Glycerine 98%	5.0
Cetyl trimethyl ammonium bromide	0.5
1-ethyl-biuret	3.0
Perfume, coloring	0.2
Water	31.3
	10

EXAMPLE 3

Hair Lotion

	Parts
Isopropyl alcohol	50.0
Propylene glycol	3.0
Beta-naphthol	0.2
1-methyl-dithiobiuret	1.0
Perfume, coloring	0.2
Water	45.6

The hair lotions of Examples 2 and 3 are prepared in a way analogous to Example 1.

EXAMPLE 4

Hair Cream

[Oil-in-water emulsion]

14 parts of diglycol laurate, 34 parts of mineral oil and 0.2 part of a preservative (e.g. methyl-p-hydroxy benzoic acid ester) are heated to 80° C. This mix is slowly and thoroughly stirred into a solution of 1 part of thiobiuret in 50.5 parts of water. After cooling to 35° C., 0.3 part of perfume is added. Finally the cream is homogenized on a roller mill.

EXAMPLE 5

Hair Cream

[Oil-in-water emulsion]

Part I	
Mineral oil	Parts 33.0
Bees wax	3.0
Stearic acid	0.5
Cetyl alcohol	1.3
Preservative	0.2

Part II	
Borax	0.25
Triethanolamine	1.85
1,5-dihydroxymethyl-biuret	5.00
Water	54.60

Part III	
Perfume	0.30

Part I is heated to 60-65° C. and slowly added with vigorous stirring to part II previously heated to 60-65° C. The cream is cooled with stirring to 35° C. at which temperature part III is added.

EXAMPLE 6

Hair Cream

[Water-in-oil emulsion]

Part I	
Bees wax	1.5
Cleic acid	1.0
Mineral oil	40.6
Preservative	0.2

Part II	
Milk of lime 0.14%	50.0
1-formyl-5-acetyl-biuret	1.0

Part III	
Magnesium sulfate solution 10%	5.0

Part IV	
Perfume	0.7

Part I is heated to 70-75° C. Then part II previously heated to 60° C. is slowly added with thorough stirring, and finally part III is introduced. The cream is stirred at 70° C. for 10 minutes and then slowly cooled with stirring to 55° C. At this temperature, part IV is added. Then the cream is cooled to 35° C. and homogenized at 30° C.

EXAMPLE 7

Liquid Shampoo

Part I

	Parts
Cleic acid	5.0
Coconut oil fatty acid	4.0
Triethanolamine	5.5
Propylene glycol	5.0
Preservative	0.2

Part II

20	Ethylene diamine tetraacetic acid sodium salt	0.5
Biuret		1.5
Water		78.0

Part III

25	Perfume	0.3

Part I is heated to 65° C. while stirring. After a homogeneous mix is obtained, part II previously heated to 35° C. is added with cautious stirring and finally part III is introduced.

EXAMPLE 8

Powder Shampoo

	Parts
Sodium lauryl isethionate	60.0
Sodium bicarbonate	34.5
1-methyl-biuret	5.0
Perfume	0.5

The solid components are homogeneously mixed in a mixer and the perfume is added by spraying it on the powder while moving the mass in the mixer.

EXAMPLE 9

Liquid Shampoo

97.4 parts of an aqueous alcoholic solution containing 20 parts of ammonium coconut oil monoglyceride monosulfate and 20 parts of ethyl alcohol are heated to 35° C. 2 parts of 1,3,5-trimethylbiuret, 0.2 part of preservative, 0.05 part of dyestuff and 0.35 part of perfume are stirred successively into this solution.

EXAMPLE 10

Liquid Shampoo

	Parts
N-lauryl-beta-amino-propionic acid triethanolamine salt, 40%	50.0
Coconut oil fatty acid diethanolamide	2.0
1,5-dimethyl-biuret	3.0
60 Perfume, preservative, coloring	0.6
Water	44.4

This composition is prepared in a similar way as described in Example 9.

EXAMPLE 11

Cream Shampoo

91.8 parts of an aqueous sodium lauryl sulfate paste containing about 45 parts of sodium lauryl sulfate are heated to 50-60° C. To this mix a melt from 2 parts of polyethylene glycol-400-distearate, 1.5 parts of magnesium stearate and 1 part of oleyl alcohol and then 0.2 part of a preservative and 3 parts of thiobiuret are added with stirring. After cooling to 40° C. 0.5 part of perfume is introduced.

EXAMPLE 12

Hair Rinse

	Parts
Stearyl dimethyl benzyl ammonium chloride	4.0
Polyglycol-400-distearate	3.0
1-hydroxymethyl-biuret	2.0
Perfume, preservative	0.5
Water	90.5

From all components an aqueous solution is prepared at room temperature. After standing for 24 hours the solution is filtered.

Although the present invention has been described with reference to particular embodiments and examples, it will be apparent to those skilled in the art that variations and modifications of this invention can be made therefor without departing from the principles and true spirit of the invention.

What is claimed is:

1. An aqueous cosmetic composition suitable for daily use in the care of the hair and scalp which comprises about 0.5 to 50% by weight of a substantially non-volatile organic toilet agent for the care of the hair, about 0.05 to 10% of a diamide compound having a formula

wherein X is selected from the group consisting of oxygen and sulfur, R₁, R₂, R₄ and R₅ are selected from the group consisting of hydrogen, alkyl, alkylol and acyl, and R₃ is selected from the group consisting of hydrogen and alkyl, said R₁, R₂, R₃, R₄ and R₅ containing up to two carbon atoms each, and from 40 to 99.45% of a volatile aqueous solvent medium, said composition having a pH of from 4 to 10 and being free of reducing agents.

2. A cosmetic composition as set forth in claim 1 wherein said diamide is biuret.

3. A shampoo composition comprising from about 5 to 98% of a water soluble organic detergent, and .05 to 10% of a diamide compound having the formula

wherein X is selected from the group consisting of oxygen and sulfur, R₁, R₂, R₄ and R₅ are selected from the group consisting of hydrogen, alkyl, alkylol and acyl, and R₃ is selected from the group consisting of hydrogen and alkyl, said R₁, R₂, R₃, R₄ and R₅ containing up to two carbon atoms each, and water as the balance, said composition having a pH of 4 to 10 and being free of reducing agents.

4. A shampoo composition as set forth in claim 3 wherein said diamide is biuret.

5. A hair grooming composition suitable for daily use in the care of the hair and scalp which comprises about 0.5 to 50% by weight of a substantially non-volatile organic hair grooming agent containing an alcoholic hydroxyl group and having a molecular weight greater than about 75, 0.05 to 10% of a diamide compound having the formula

wherein X is selected from the group consisting of oxygen and sulfur, R₁, R₂, R₄ and R₅ are selected from the group consisting of hydrogen, alkyl, alkylol and acyl, and R₃ is selected from the group consisting of hydrogen and alkyl, said R₁, R₂, R₃, R₄ and R₅ containing up to two carbon atoms each, and 40 to 99.45% of a volatile aqueous solvent medium, said composition having a pH of 4 to 10 and being free of reducing agents.

6. A hair grooming preparation as set forth in claim 5 wherein said hair grooming agent is glycerine.

7. A process for the treatment of the hair and scalp which comprises the daily application thereto of a substantially non-volatile toilet agent for the daily care of the hair and about 0.05 to 10% by weight of a diamide compound having the formula

wherein X is selected from the group consisting of oxygen and sulfur, R₁, R₂, R₄ and R₅ are selected from the group consisting of hydrogen, alkyl, alkylol and acyl, and R₃ is selected from the group consisting of hydrogen and alkyl, said R₁, R₂, R₃, R₄ and R₅ containing up to two carbon atoms each, the said toilet agent and diamide compound being applied to the hair and scalp at a pH of 4 to 10.

8. A cosmetic composition suitable for daily use in the care of the hair and scalp which comprises a substantially non-volatile toilet agent for the daily care of the hair and from about 0.25 to 2.0% by weight of a diamide compound having the formula

wherein X is selected from the group consisting of oxygen and sulfur, R₁, R₂, R₄ and R₅ are selected from the group consisting of hydrogen, alkyl, alkylol and acyl, and R₃ is selected from the group consisting of hydrogen and alkyl, said R₁, R₂, R₃, R₄ and R₅ containing up to two carbon atoms each, said composition having a pH of 4 to 10 when disposed in an aqueous liquid and being free of reducing agents.

9. A cosmetic composition suitable for daily use in the care of the hair and scalp which comprises a substantially non-volatile toilet agent for the daily care of the hair and from about 0.25 to 1.0% by weight of a diamide compound having the formula

wherein X is selected from the group consisting of oxygen and sulfur, R₁, R₂, R₄ and R₅ are selected from the group consisting of hydrogen, alkyl, alkylol and acyl, and R₃ is selected from the group consisting of hydrogen and alkyl, said R₁, R₂, R₃, R₄ and R₅ containing up to two carbon atoms each, said composition having a pH of 4 to 10 when disposed in an aqueous liquid and being free of reducing agents.

10. A cosmetic composition suitable for daily use in the care of the hair and scalp which comprises a substantially non-volatile toilet agent for the daily care of the hair and from about 0.05 to 10% by weight of a diamide having the formula

wherein X is selected from the group consisting of oxygen and sulfur, R₁, R₂, R₄ and R₅ are selected from the group consisting of hydrogen, alkyl, alkylol and acyl, and R₃ is selected from the group consisting of hydrogen and alkyl, said R₁, R₂, R₃, R₄ and R₅ containing up to two carbon atoms each, said composition having a pH of 4 to 10 when disposed in an aqueous liquid and being free of reducing agents.

11. A hair grooming composition suitable for daily use in the care of the hair and scalp which comprises about

0.5 to 50% by weight of mineral oil, 0.05 to 10% of a diamide compound having the formula

5

wherein X is selected from the group consisting of oxygen and sulfur, R₁, R₂, R₄ and R₅ are selected from the group consisting of hydrogen, alkyl, alkylol and acyl, and R₃ is selected from the group consisting of hydrogen and alkyl, said R₁, R₂, R₃, R₄ and R₅ containing up to two carbon atoms each, and 40 to 99.45% of a volatile aqueous solvent medium, said composition having a pH of 4 to 10. 10
